UNITED STATES PATENT OFFICE.

JOHN M. KELLEY, OF ROCHESTER, NEW YORK, ASSIGNOR TO PROTANE CORPORATION, OF ERIE, PENNSYLVANIA.

LIQUID-HYDROCARBON BURNER.

Application filed February 14, 1925. Serial No. 9,200.

The present invention relates to liquid hydro-carbon burners and an object of the invention is to provide an improved mixing chamber which has special advantages when used in connection with ovens, ironing machines, printing presses and numerous other apparatus and particularly where the mixing chamber is arranged exteriorly of the chamber in which the burning takes place or at a point removed from such place of burning. Another object of the invention is to provide a burner with a mixing device at a point removed therefrom, such mixing device having a warming flame which will act also for igniting the burner. Still another object of the invention is the inter-relation between a plate burner and an oven burner so that either may be employed for the ignition of the other. A still further object of the invention is the inter-relation between a plate burner and an oven burner so that one warms the drier or expansion chamber of the other. A still further object is the provision of a means which will prevent the ready access to the valve for turning on the gas of the oven burner while the door of the oven into which the gas is discharged and burned is in a closed position.

To these and other ends, the invention consists of certain parts and combinations of parts, all of which will be hereinafter described: the novel features being pointed out in the appended claims.

In the drawings:

Fig. 1 is a front view of a gas range embodying the present invention;

Fig. 2 is a horizontal section of the gas range above the burners;

Fig. 3 is a view of the underside of the oven burner showing its relation to one of the plate burners;

Fig. 4 is a side view of the mixer of the oven burner partially in section;

Fig. 5 is a horizontal section of the mixing chamber of the oven burner;

Fig. 6 is a view of the drying device partially in section and partially in plan;

Fig. 7 is a sectional view showing the flexible connection between an expansion

chamber and the fuel conducting pipe; and

Fig. 8 is a longitudinal section of the burner for warming the expansion chamber of the oven burner and igniting the oven burner.

Fig. 9 is a fragmentary view showing the manner in which the burner tube passes through the oven casing.

The present invention is designed particularly for burning liquid hydro-carbon fuels of the type having a dry end point not in excess of 150° F. and an initial boiling point of approximately 45° F. or lower and which will not develop pressure in excess of fifty pounds at 100° F. Such a fuel is obtainable from the gas escaping from oil sands in the production of crude oil and known to the trade as casinghead gas. This casinghead gas is represented by the following compounds:

Methane CH_4 , ethane C_2H_6 , propane C_3H_8 , butane C_4H_{10} , pentane C_5H_{12} , hexane C_6H_{14} , heptane C_7H_{16} .

These belong to the same chemical family but with different physical characteristics. The first compound is a gas about one-half as heavy as air and requiring about the same pressure and temperature as air to liquefy. The second compound is also a gas at ordinary temperatures and pressures, requiring about seven hundred pounds pressure and a temperature of 40° F. to liquefy. The third compound is a gas of ordinary pressure and temperature, but liquefies at two hundred and fifty pounds at a temperature of 63° F. The fourth compound is a liquid at atmospheric pressure at a temperature of 32° F. The fifth compound is a liquid at 60° F., at atmospheric pressure, and forms one of the lighter fractions of commercial gasoline. The sixth and seventh products are the main constituents of commercial gasoline.

This invention is designed for burning the intermediate products of the casinghead gas which will not develop a pressure in excess of fifty pounds at 100° F. and which has a dry end point not in excess of 150° F. and an initial boiling point of approximately 45° F. or lower.

In an application filed by me on the 18th day of June, 1923, Serial No. 645,945, I have disclosed an apparatus for burning the aforesaid liquid hydro-carbon fuel and a burner used in such method. The present invention embodies improvements over the invention claimed in my aforesaid application.

The present invention is herein shown as illustrated in a gas range with an oven although it will be apparent that the invention is not limited to this use of the invention. Referring more particularly to the drawings, 1 indicates the range having a top plate 2, a bake oven 3 and a broiler oven 4. The gas in liquid form is received from a suitable source through a pipe 5 and is conducted by said pipe to the driers or expansion chamber 6, 7, 8, 9 and 10 of the different burners. In this instance, the coupling head 11 of each burner 6, 7, 8, 9 and 10 has a port or opening surrounded by a seat 12 for one end of a conductor pipe 13. This seat has an enlarged bore 14 thereabout formed with screw thread walls with which external threads on a bushing 15 are adapted to engage. The end of this bushing is feathered at 16 in order to cooperate with a camming or wedging wall 17 formed on the drier head 11 and adapted to press the feathered edge or portion 16 onto the coupling pipe 13, thereby providing a flexible yet gastight connection between the driers or expansion chambers and the fuel supply. The coupling member or head 11^a of the drier 10 being the last in the series has only one of the flexible connections secured to it.

The driers or expansion chambers 6, 7, 8, 9 and 10 are the same as that claimed in my application aforesaid Serial No. 645,945. In this illustrated embodiment they are identical in construction except as to length so that a description of the drier 10 will serve for all. This drier or fuel delivery device comprises an elongated expansion chamber having the coupling member 11^a secured to one end thereof and having a bushing 18 at the other end formed with a discharge orifice 19. This elongated expansion chamber has its walls formed with a material of high heat conductivity such as brass or copper. Within this tube or expansion chamber a helix 20 may be arranged extending from the coupling member 11^a substantially to the bushing, this helix having a central opening in which a controlling member or needle 21 is operated. One end of this needle has a screw threaded portion 22 turning in the coupling member 11^a and provided with a handle or turning wheel 23 on the exterior of the coupling member. The other end of this needle is provided with a long sharp pointed tapering end 24 which operates in the cylindrically formed orifice 19 in the bushing 18. The helix acts

as a guide for the stem of the needle and the pointed tapered end acts to measure the amount flowing through the orifice in its extreme end, the orifice being entirely closed when the cylindrical portion of the stem 70 enters the cylindrical orifice.

Each drier 6, 7, 8 and 9 projects slidably into a mixing device, the same, in this instance, as disclosed in my application Serial No. 645,945 aforesaid, and comprising generally a mixing chamber 25 in the form of a return bend connecting with the burner head 26, the mixing chamber having an air inlet opening controlled by an adjustable air inlet valve 27.

Each mixing chamber 25 and burner of the driers 6, 7, 8, and 9 are secured by bolts 25^a to a supporting bar 25^b of which there are two, one for the driers 6 and 8 and the other for the driers 7 and 9. The valves 27 are situated above these bars and have their outward movements limited by the bars. The oven burner embodies the main burner portion 28, in this instance in the form of a rectangular frame with a central leg arranged in the broiler oven beneath the bottom of the baking oven and supported through lugs 29 on brackets 30 secured to the side wall of the range. The wall 31 adjacent the plate 2 is provided with a collared opening 32 and in this collar a laterally extending arm 33 on a mixing chamber 34 of the oven burner extends, the arm 33 being enlarged to receive a lateral projection 35 on the burner member 28 and this lateral projection 35 being secured in the arm 33 by a bolt 36. The collar has a recess 33^a below the arm 33 for a purpose to be described.

The mixing chamber of the oven burner extends from the arm 35 rearwardly and downwardly at 37 and then by an upward and forward bend 38 connects with a forwardly extending portion 39, thereby forming a trap for any unvaporized fuel. At the forward end of this arm a depending portion 40 is provided having an air opening controlled by an adjustable valve 41, whereby the amount of air entering the mixing chamber formed by the portions 37, 38 and 39 may be controlled or adjusted. Above the air opening, the mixer chamber has a sub-chamber 42 which through a contracted portion 43 connects with the main portion of the mixing chamber. Into this sub-chamber 42 the end of the drier 44 slidably projects so that the fuel issuing from the orifice 19 first partially expands in the chamber 42 in the presence of air and then the mixture passes through the contracted opening 43, so that a final expansion takes place in the main chamber of the mixer.

Extending forwardly from the body of the mixer is an arm 44 having an opening 45 at its forward end aligned with the open- 13

ing in the chamber 42 so that the drier or ¹⁶⁵ been warmed, the heat from the burner will ¹⁶⁵ expansion tube 10 will be supported in alignment with the expansion chamber of such ¹⁷⁰ movement with the opening in the chamber 42. burner in a warm condition, due to the fact. This arm 44 also has a passageway or chamber ¹⁷⁵ that the flame from any burner 26 plays on burner 46 which connects with the mixing ¹⁸⁰ its respective expansion chamber. This also chamber adjacent the arm 33 and runs ¹⁸⁵ supplies to the burners connected to the expansion chamber 10, 7 and 9. It will be noted ¹⁹⁰ This chamber 46 is provided with a series ¹⁹⁵ that in the turning of the valve to raise or of jet openings or perforations 47 which lower the flame, the amount of warmth pro- ²⁰⁰ 10 extend onto the arm 33 and connect with the expansion chambers ²⁰⁵duced upon all of the expansion chambers ²¹⁰ the jet openings 48 formed on the project ²¹⁵ 6 to 10, inclusive, will vary so that a uni- ²²⁰ 15 projection 35 and connecting with the jet openings ²²⁵ form rate of expansion is maintained in ²³⁰ 49 on the burner frame. It is thus apparent ²³⁵ the burner corresponding to the size of the ²⁴⁰ 20 or burner 47 travels throughout the length ²⁴⁵ of the chamber 46 along the arm 33 and warming the expansion chamber 10 from ²⁵⁰ 25 projection 35 to the jet openings 49 of one of the other burners, and with this ob- ²⁵⁵ 15 main portion of the burner. The end of the jet in view, the burner connected to the ex- ²⁶⁰ 20 the arm 33 is bevelled at 50 on its underside ²⁶⁵ pansion chamber 8 has a lateral extension ²⁷⁰ 25 and this bevelled portion has perforations ²⁷⁵ 51 which connects with the mixing chamber ²⁸⁰ 30 20 of the projection 35 so that the flame ²⁸⁵ 25 of said burner and has its end lying in ²⁹⁰ 25 proximity to an exposed portion of the ex- ²⁹⁵ 25 pansion chamber 10 in immediate proximity ³⁰⁰ 30 to the jet openings 47. This tubular exten- ³⁰⁵ 25 sion or conductor is provided with a burner ³¹⁰ 30 and also serve to ignite the main burner as ³¹⁵ 35 soon as sufficient gas has reached the cham- ³²⁰ 35 ber of such burner, when the gas is turned ³²⁵ 40 on. The nature of the fuel is such that the ³³⁰ 40 flame of a match upon being applied to the extension to the underside, then along the ³³⁵ 45 exposed portion of the expansion chamber ³⁴⁰ 45 underside toward the end which is bevelled ³⁴⁵ 50 30 between the outer end 45 of the arm 44 at 53 and provided with jet openings to con- ³⁵⁰ 55 and the discharge end of the expansion ³⁵⁵ 50 duct the flame to the jet openings in the ex- ³⁶⁰ 60 chamber will warm the gas to such an extent ³⁶⁵ 55 as to overcome the reduction of temperature ³⁷⁰ 60 set up by the expansion of the gas under ³⁷⁵ 60 pressure to permit the gas to issue freely ³⁸⁰ 65 from the orifice in a dry state without chill- ³⁸⁵ 65 ing, condensing or congealing into the mix- ³⁹⁰ 70 ing chamber above the air opening. Almost ³⁹⁵ 70 immediately a gas will travel through the mixing chamber, some passing to the pas- ⁴⁰⁰ 75 sageway 46 through the jet openings or ⁴⁰⁵ 80 burner 47 to allow such gas to be ignited ⁴¹⁰ 85 by the match or other small flame produc- ⁴¹⁵ 85 ing device which is utilized for warming the drying tube. At the same time the flame ⁴²⁰ 90 will travel from the orifices or jets of the igniting burner to the jets of the main ⁴²⁵ 95 burner.

It will be noted that the burners 26 which are fed by the expansion chambers 6 and 8 are situated in close proximity to the expansion chambers 7 and 9 respectively. This arrangement makes it possible to warm the expansion chambers 7 and 9 from the burners supplied by the expansion chambers 6 and 8 and as a consequence no preliminary warming with a match is required by the chambers 7 and 9 when the adjacent burners are in use. The expansion chambers 6 and 8 must be warmed by a match or other flame producing device before the valves thereof are operated. After the gas has ¹¹⁰ 100 ¹¹⁵ 105 ¹²⁰ 125 ¹²⁵ 130 ¹³⁰ 135 ¹³⁵ 140 ¹⁴⁰ 145 ¹⁴⁵ 150 ¹⁵⁰ 155 ¹⁵⁵ 160 ¹⁶⁰ 165 ¹⁶⁵ 170 ¹⁷⁰ 175 ¹⁷⁵ 180 ¹⁸⁰ 185 ¹⁸⁵ 190 ¹⁹⁰ 195 ¹⁹⁵ 200 ²⁰⁰ 205 ²⁰⁵ 210 ²¹⁰ 215 ²¹⁵ 220 ²²⁰ said jet openings will be conducted to the jet openings 49 of the burner.

With the end in view of preventing the operation of the oven burner prior to the opening of one of the oven doors, so that the gas cannot accumulate in the oven and produce an explosion, the broiler oven door 4^a is provided with an arm 54 which has at its outer end a flanged disk or cap 55 of a size 10 to cover the operating wheel or handle 23 of the valve of the expansion chamber 10. This cap when the door is open exposes the handle or wheel 23 for operation. As a consequence, it is impossible readily to turn the 15 handle or wheel without opening the door of the broiler oven. It is desirable to place this valve covering device upon a broiler door in preference to arranging it upon the door of the main oven as the gas, if issued unburned 20 from the burner at all, being heavier than air will accumulate mostly in the broiler oven and will with the opening of the door, fall or pass out from such oven.

With this invention, it is possible to ignite 25 a burner situated at a distance from the mixing chamber by means of an auxiliary or warming burner which is utilized for warming an expansion chamber which delivers gas into the mixing chamber, this result being secured, in this instance, by providing a 30 connection between the distant burner and the mixing chamber which has a series of jet openings connecting the jet opening of the warming burner with the jet openings of the distant burner. A mixing chamber is 35 provided which has a sub-chamber separated from the main portion by a restricted passageway and provided with an air inlet opening, so that the gas expands in passing 40 into the main portion after being delivered to the sub-chamber. The mixing chamber has beyond the restricted passageway two arms one of which connects with the warming burner and the other of which leads to 45 the main or distant burner. Furthermore, two mixing chambers are provided each having 50 its own expansion chamber to deliver gas therein and one of which has a burner connected with its mixing chamber and so arranged that a flame from such mentioned burner will warm the expansion chamber of the other burner. In one form, the expansion chambers are elongated, one being longer than the other and the two burners are 55 arranged one in rear of the other, the forward burner being arranged to warm both expansion chambers and the rear burner being arranged to warm only the expansion chamber connected to it. There is also provided 60 a construction in which two expansion chambers are employed each of which has two burners, one of such burners being utilized for warming its expansion chamber and the other burner connected with such 65 expansion chambers being utilized for

warming the expansion chamber of the other two burners, and igniting the warming burner of such other two burners whereas the warming burner of such other two burners is employed for igniting the other burner 70 of such other two burners. A range is provided which has an upper and lower oven, the door of the lower oven being employed for preventing the operation of the valve which controls the burners for heating both 75 ovens.

What I claim as my invention and desire to secure by Letters Patent is:

1. The combination with a main burner, 80 of an air mixing chamber arranged at a distance from the main burner, an expansion chamber arranged in close proximity to the air mixing chamber and at a distance from the main burner and discharging in the air mixing chamber, means for delivering liquid 85 fuel into said expansion chamber, a second burner arranged in proximity to the expansion chamber and at a distance from the main burner and receiving gas from the air mixing chamber, said burner playing upon 90 the expansion chamber to maintain the latter in a warm condition, and a gas conducting connection between the two burners through which the main burner receives its 95 supply of fuel from the air mixing chamber, said connection being formed with a train of jet openings maintaining a continuous flame connection between the two burners, so that either may be lighted from the other and both burners will be maintained in a lighted condition. 100

2. The combination with a chamber and an elongated expansion chamber into which a liquid fuel is delivered arranged exteriorly 105 of the first mentioned chamber, of an air mixing chamber into which the gas from the expansion chamber is discharged, arranged exteriorly of the first mentioned chamber, an arm arranged exteriorly of the first mentioned chamber extending from the mixing 110 chamber along the expansion chamber and provided with a warming burner for the expansion chamber arranged exteriorly of the first mentioned chamber a main burner arranged within such first mentioned chamber, 115 and a connection between the mixing chamber and the main burner having jet openings leading to the burner of said arm to conduct the flame to the burner from the warming burner. 120

3. The combination with an elongated expansion chamber into which the liquid fuel is delivered, of an air mixing chamber into which gas from the expansion chamber is discharged, an arm extending from the mixing chamber and provided with a warming burner for the expansion chamber receiving gas from the mixing chamber and arranged to be ignited by a flame producing device employed for initially 125 130

warming the expansion chamber, a main burner, and connection between the main burner and the mixing chamber embodying arms on both elements, one received within the other, the receiving arm having a bevelled end and both arms being provided with jet openings which extend through the bevelled portion and conduct a flame from the warming burner to the main burner without a break.

4. The combination with a chamber to be heated and an expansion chamber arranged exteriorly of the first mentioned chamber, of a main burner within the first mentioned chamber, an air mixing chamber into which the expansion chamber delivers fuel, arranged exteriorly of the first mentioned chamber, a connection between the air mixing chamber and the main burner through which the main burner receives its supply of fuel from the mixing chamber, and a train of jet openings leading from the main burner through said connection to a point adjacent the expansion chamber so that a flame employed for warming the expansion chamber will, through said train of jet openings, ignite the main burner.

5. The combination with a chamber and an expansion chamber into which liquid fuel is delivered arranged exteriorly of the first mentioned chamber, of a mixing chamber arranged exteriorly of the first mentioned chamber and having two parts separated by a restricted passageway, one of said parts having gas from the expansion chamber discharged therein and being provided with an air opening, two burners receiving gas from the other part of the mixing chamber, one of said burners being arranged exteriorly of said first mentioned chamber and acting to warm the expansion chamber, and the other of said burners being arranged within said first mentioned chamber, and means for conducting a flame from such warming burner to the other burner to ignite the latter.

6. The combination with an expansion chamber into which liquid fuel is delivered, of a mixing chamber having two parts separated by a restricted passageway, one of said mixing chamber parts having gas from the expansion chamber discharged therein and being provided with an air opening and the other of said parts having a return bend and being provided with two arms, one of which extends along the expansion chamber and is provided with a warming burner for the expansion chamber receiving gas from the mixing chamber and the other of which extends laterally and is provided with jet openings communicating with the warming burner of the first mentioned arm, and a burner connected with the last mentioned arm to be ignited by a flame from the warming burner of such arm.

7. The combination with a stove and two

elongated expansion chambers arranged horizontally side by side on the stove, one of said expansion chambers being longer than the other, of two mixing chambers, one receiving gas from each expansion chamber, and two burners each associated with one mixing chamber, that burner connected with the mixing chamber associated with the longer expansion chamber lying on the stove in rear of the other burner, and the forward burner lying between the two expansion chambers, each of said burners having jet openings from which flame plays upon the expansion chamber from which the burner receives its gas to warm said expansion chamber, and the burner connected with the shorter expansion chamber also having jet openings from which a flame passes to warm the longer expansion chamber, whereby the rear burner may be ignited without any initial warming of the expansion chamber by an igniting device.

8. The combination with a chamber to be heated, of two main burners, one arranged in said chamber and the other arranged without the chamber, two air mixing chambers, both situated outside of the chamber to be heated, two gas conducting connections, one leading from one air mixing chamber to the burner outside of the chamber to be heated and the other leading from the other air mixing chamber to the burner within the chamber to be heated, two expansion chambers for delivering fuel into the two air mixing chambers, both situated outside of the chamber to be heated, an auxiliary burner arranged to warm that expansion chamber which feeds fuel to the main burner within the chamber to be heated, said auxiliary burner receiving its supply of fuel from the mixing chamber of said main burner, the gas conducting connection between the main burner of the chamber to be heated and the mixing chamber of said main burner being provided with a train of jet openings for conducting a flame from the auxiliary burner to the main burner, and another auxiliary burner communicating with the mixing chamber of that main burner which is located outside of the chamber and arranged so that the flame therefrom may play on the expansion chamber of the main burner located within the chamber to be heated and also supply a flame to the auxiliary burner of the main burner located within the chamber to be heated.

9. The combination with an expansion chamber, of a mixing chamber receiving gas from the expansion chamber, two burners associated with said mixing chamber, one of said burners being situated at such a distance from the expansion chamber as not to materially affect the temperature thereof, the other of said burners being arranged so as to warm said expansion chamber, means

for connecting the first mentioned burner with the last mentioned burner so that the ignition of the last mentioned burner effects the ignition of the distant burner, a second expansion chamber, a mixing chamber receiving gas therefrom, and means connecting with said last mentioned mixing chamber

ber for warming the last mentioned expansion chamber and also for warming the first mentioned expansion chamber and for igniting the warming burner of said first mentioned expansion chamber. 10

JOHN M. KELLEY.
